UNITED STATES PATENT OFFICE.

NATHAN M. LOWER, OF PITTSBURGH, PENNSYLVANIA, ASSIGNOR TO LOCOMOTIVE STOKER COMPANY, A CORPORATION OF PENNSYLVANIA.

LOCOMOTIVE-STOKER.

1,375,711.

Specification of Letters Patent. Patented Apr. 26, 1921.

Application filed May 26, 1917. Serial No. 171,209.

To all whom it may concern:

Be it known that I, NATHAN M. LOWER, a citizen of the United States, and resident of Pittsburgh, county of Allegheny, and 5 State of Pennsylvania, have invented certain new and useful Improvements in Locomotive-Stokers, of which the following is a specification, and which are illustrated in the accompanying drawings, forming a part 10 thereof.

The invention relates to stokers of the so-called inside feed type, in which the fuel is delivered from a suitable conveyer to the interior of the fire-box of the locomotive 15 and then distributed over the grate area.

The object of the invention is to provide a simple and efficient stoker of this type involving various improvements in the general construction, and in many of the details, whereby the fuel is advanced at a suitable rate and with a minimum expenditure of power, being reduced to the proper size as it passes through the conveying mechanism. The invention also involves an improvement in the means of driving and reversing the conveyer and crusher, and for automatically varying the operation of the means for distributing the fuel within the fire-box, all as hereinafter fully pointed out.

30 In the accompanying drawings—

Figure 1 is a detail vertical longitudinal section of the locomotive and its tender and of the stoker mechanism;

Fig. 2 is a detail of a joint for connecting 35 adjacent sections of the conveyer screw;

Fig. 3 is a detail transverse section of the conveyer taken through the driving mechanism and crusher, and showing the actuating motor partly in elevation;

40 Figs. 4 and 5 are detail plan views of a portion of the driving mechanism of the conveyer, showing the parts in different positions;

Fig. 6 is a detail of the ratchet and pawl mechanism for transmitting power to the conveyer;

Fig. 7 is a transverse sectional view of the conveyer showing the driving mechanism and means for variably controlling the fuel 50 scattering mechanism; and

Fig. 8 is a detail of the regulating valve by means of which the scattering action is varied.

55 A portion of the fire-box of a locomotive is shown at 10, its chambered back wall

being represented at 11. The locomotive deck or floor of the cab is shown at 12. At 13 is shown the floor of the fuel bin of the tender, in which is formed at 14 an aperture for permitting the fuel to fall by 60 gravity into the trough 15 of the conveyer.

The conveyer trough and the conduit 16 leading forwardly therefrom are supported by means of a stirrup 17 in a manner common in devices of this character, and the 65 rearward section of the conduit is united to the next section 18 thereof, which is suitably supported from the locomotive, by a ball and socket joint 19, to permit the relative movement of the tender and locomotive 70 without injury to the transferring mechanism. To the forward end of the conduit 18 is attached an upwardly inclined section 20, and to the forward end of this section is attached a section 21, sharply upwardly inclined and passing through the grate 22 of the fire-box, its upper end being open to permit the discharge of fuel.

Within the trough 15 and the conduit sections 16, 18, 20 and 21 is located a screw 80 conveyer comprising the sections 23, 24, 25 and 26. The conveyer sections 23 and 24 are united by a universal joint 27, inclosed within the ball and socket joint 19. The sections 24, 25, and 26, are rigidly united, 85 the elbows being enlarged and preferably taking the form of sections of a sphere, as shown at 30, 30, in order to provide ample space for the passage of fuel in view of the space occupied by the joints connecting 90 the conveyer sections. The shafts 31, 32, of the conveyer sections 24, 25, are connected by a ball and socket joint 28 of sufficient size to inclose a pair of intermeshing bevel gears 33, 34, fixed upon the shaft ends. A 95 supplemental ball and socket joint 35 is preferably provided at the axes of the shafts. The shafts of the conveyer sections 25, 26, are similarly united.

A reciprocating motor 37, suitably supported below the floor of the locomotive cab and transverse thereto, is preferably steam actuated, and is provided with the necessary steam connections, not shown. To the end of the piston rod 38 of the motor is attached 10 a gear rack 39, reciprocating in a suitable bearing 40 and meshing with an annular gear wheel 41 housed within a casing 42, inclosing the conduit section 18, a portion 11 of which is cut away within the casing to

accommodate the driving gears. The gear wheel 41 is mounted to freely turn upon an annular shell 43, forming the periphery of a two spoke wheel fixed upon the shaft 31 of the conveyer section 24. The spokes 44, 45, constitute the crushing means for reducing the fuel.

A lateral extension 46 of the gear 41 takes the form of a ratchet wheel coöperating with 10 a two-nosed pawl 47, pivotally mounted upon an eccentric annular rib or ring 48 carried by the shell 43. The reciprocation of the motor, therefore, causes the oscillation of the annular gear 41, and this communicates a step by step movement to the wheel 43 and through it to the several conveyers. The pawl 47 is held in driving position by means of a spring 49, attached at one end to a lever 50 which is pivoted to the eccentric, and at the other end directly to the eccentric. The connection between the lever arm 50 and the pawl is through the medium of a pair of links 51, 52, the former attached to a barrel 53 and the other to a head 54 reciprocating within the barrel and seated between a pair of helical springs 55, 56, reacting against the ends of the barrel.

A shifting ring 57, sleeved upon the conduit section 18 and controlled by a hand lever 58 extending upwardly through the floor 12 of the cab and pivoted to the casing 42, as shown at 59, coöperates with a roller 60 carried by the free end 61 of the lever 50, and when advanced swings this lever in 35 position to the spring 49 and tilts the pawl 47 from the position shown in Figs. 3 and 6 to throw its opposite nose into engagement with the teeth of the ratchet 46, for the purpose of turning the latter and the crusher 40 and conveyer mechanism in the reverse direction. This reversing action is provided for the purpose of freeing the crusher and conveyer from any extraneous matter, such as chunks of metal or stone, which may find 45 their way into the fuel.

The fuel is distributed by means of a steam jet discharged from a nozzle 62 directly across the open end of the conduit section 21, and entering through the fire-box 50 wall 11. For the purpose of scattering the fuel to all parts of the fire-box, provision is made for varying the pressure of this steam jet, such provision consisting in the 55 present instance of a choke valve and means for automatically shifting the valve to regulate the volume of steam delivered to the nozzle 62. As shown, this valve is inclosed within a casing 63, suitably supported by means of brackets 64, 65, from the floor of 60 the cab and provided with a nipple 66, to which a suitable service pipe is connected, and with a nipple 67 to which a pipe 68 leading to the nozzle is attached. The choke valve 69 is tapering in form and regulates 65 an opening 70 in a diaphragm 71 interposed

between the nipples 66, 67, a spring 72 urging it toward the diaphragm.

A sectional valve stem 73, adjustable as to length by means of a turn buckle 74, is connected to a lever 75. This lever is pivoted at 76 to an adjusting rod 77, controlled by a nut 78 riding upon a suitable bracket, as 79, the free end of the lever 75 having a bearing upon the eccentric rib or ring 48, and being provided with an anti-friction roller 75 80 running thereon. A spring 81, reacting between the lever 75 and a fixed abutment 82, holds the lever against the eccentric and tends to close the valve 69, supplementing the spring 72.

With the rotation of the eccentric 48 the position of the valve 69 is constantly changed, thereby correspondingly varying the volume of steam delivered to the nozzle and consequently the force of the jet effect- 85 90 ing the distribution of the fuel. By turning back the nut 78 the fulcrum 76 of the lever is allowed to descend, permitting the valve to approach its seat under the influence of the springs, thereby reducing the minimum volume of steam admitted to the nozzle. The range of movement of the valve, due to the turning of the eccentric, remaining the same, it follows that the maximum volume of steam is correspondingly reduced.

In all furnaces the force necessary to deliver to front and near portion of the grate is the same, while that required to impel the fuel to the rear or more remote portion of the grate depends upon the length of the 100 fire-box. In order to adapt the device to the particular engine to which it is to be applied, it is therefore desirable to provide means for varying the range of movement of the valve 69. This is conveniently accomplished by providing a shiftable connection between the valve stem 73 and the lever 75. Such connection may be secured by laterally extending the lower end of the stem, as shown at 83, forming in such extension a 105 transverse slot 84, and in the lever a longitudinal slot 85. The lower end of the valve stem is bifurcated to straddle the lever. The pivot pin 86 uniting the stem and lever is provided with a nut for clamping it firmly 110 to the stem. The pin may, therefore, be set in any desired position in the two slots and securely held in place by means of the nut, and the extent of the lifting movement will be determined by the distance of the pin 120 from the movable end of the lever.

The device having been applied to a furnace and the pin 86 having been properly set to secure the desired action of the valve, no further adjustment thereof will be required.

While a simple and efficient form of construction is disclosed, various changes of detail may be made without departing from the scope of the invention.

I claim as my invention—

1. The combination with a locomotive having a fire-box and a tender having a fuel bin, of a screw conveyer leading from the tender below the fuel bin and discharging into the fire-box, a steam nozzle directed upon the fuel discharged from the conveyer and having constant communication with a source of steam supply, and means for automatically varying the intensity of the jet delivered from the nozzle. 7
2. In a locomotive stoker, in combination, a locomotive having a fire-box, a tender having a fuel bin, a conduit leading forwardly below the bin and having its delivery end inclined upward, a sectional screw conveyer within the conduit and having adjacent sections connected by a ball and socket joint, and intermeshing bevel gears mounted on the shafts of the sections and inclosed within the joint. 75
3. In a locomotive stoker, in combination, a locomotive having a fire-box, a tender having a fuel bin, a screw conveyer leading from the tender below the fuel bin and discharging through the fire-box grate, a wheel mounted on the shaft of the screw, the rim of the wheel forming a section of the conduit, a geared annulus mounted on the rim 80 of the wheel, ratchet and pawl connection between the wheel and annulus, and a power-actuated rack bar engaging the annulus. 85
4. In a locomotive stoker, in combination, a locomotive having a fire-box, a tender having a fuel bin, a screw conveyer leading from the tender below the fuel bin and discharging through the fire-box grate, a wheel mounted on the shaft of the screw, the rim 90 of the wheel forming a section of the conduit, a geared annulus mounted on the rim of the wheel, ratchet and pawl connection between the wheel and annulus, the ratchet being formed on the annulus and the pawl being carried by the wheel, and a power-actuated rack bar engaging the annulus. 95
5. In a locomotive stoker, in combination, a locomotive having a fire-box, a tender having a fuel bin, a screw conveyer leading from the tender below the fuel bin and discharging through the fire-box grate, a wheel mounted on the shaft of the screw, the rim 100 of the wheel forming a section of the conduit, a geared annulus mounted on the rim of the wheel, ratchet and pawl connection between the wheel and annulus, a power-actuated rack bar engaging the annulus, and means for reversing the pawl. 105
6. In a locomotive stoker, in combination, a locomotive having a fire-box, a tender having a fuel bin, a screw conveyer leading from the tender below the fuel bin and discharging through the fire-box grate, the vane of the screw and its casing being interrupted, a wheel fixed on the shaft of the 110
7. In a locomotive stoker, in combination, a locomotive having a fire-box, a tender having a fuel bin, a screw conveyer leading from the tender below the fuel bin and discharging through the fire-box grate, the vane of the screw and its casing being interrupted, a wheel fixed on the shaft of the screw at its interrupted section, the rim of the wheel filling the space at the interruption of the casing, a geared annulus mounted on the wheel, ratchet and pawl connection between the annulus and the wheel, and means for oscillating the annulus. 115
8. In a locomotive stoker, in combination, a locomotive having a fire-box, a tender having a fuel bin, a fuel conveyer leading from the bin and discharging into the fire-box, a steam nozzle directed on the fuel delivered by the conveyer, a constantly open choke valve in the service pipe of the nozzle, and means for alternately opening and partially closing the valve. 120
9. In a locomotive stoker, in combination, a locomotive having a fire-box, a tender having a fuel bin, a fuel conveyer leading from the bin and discharging into the fire-box, a steam nozzle directed on the fuel delivered by the conveyer, and means for delivering an undulating jet of steam from the nozzle. 125
10. In a locomotive stoker, in combination, a locomotive having a fire-box, a tender having a fuel bin, a fuel conveyer leading from the bin and discharging into the fire-box, a steam nozzle directed on the fuel delivered by the conveyer, a constantly open choke valve in the service pipe of the nozzle having a stem, a power driven eccentric upon which the valve stem is supported, and a spring tending to close the valve. 130
11. In a locomotive stoker, in combination, a locomotive having a fire-box, a tender having a fuel bin, a fuel conveyer leading from the bin and discharging into the fire-box, a steam nozzle directed on the fuel delivered by the conveyer, a constantly open choke valve in the service pipe of the nozzle having a stem, a lever to which the valve stem is connected, a power driven eccentric upon which one end of the lever bears, and a spring tending to close the valve. 135
12. In a locomotive stoker, in combination, a locomotive having a fire-box, a tender having a fuel bin, a fuel conveyer leading from the bin and discharging into the fire-box, a steam nozzle directed on the fuel de-

livered by the conveyer, a constantly open choke valve in the service pipe of the nozzle having a stem, a lever to which the valve stem is connected, a power driven eccentric 5 upon which one end of the lever bears, a spring tending to close the valve, and means for shifting the fulcrum of the lever.

13. In a locomotive stoker, in combination, a locomotive having a fire-box, a tender 10 having a fuel bin, a screw conveyer leading from the tender below the fuel bin and discharging through the fire-box grate, a wheel mounted on the shaft of the screw, the spokes of the wheel constituting fuel crushers, a geared annulus mounted on the rim of the wheel, ratchet and pawl connection between the wheel and annulus, and a power-actuated rack bar engaging the annulus.
14. In a locomotive stoker, in combination, a fire-box, a fuel bin, a conveyer leading 20 from the fuel bin and delivering into

the fire-box above the level of the grate thereof, and means for directing a continuous undulating blast of fluid under pressure against the fuel delivered by said conveyer. 25

15. In a locomotive stoker, in combination, a locomotive having a fire-box, a tender having a fuel bin, a conveyer adapted to convey fuel from the bin and deliver it into 30 the fire-box, means to direct a continuous blast of fluid under pressure against said fuel as it is discharged from the conveyer, and means to increase and decrease the intensity of said blast at a uniform rate. 35

16. A stoker comprising, in combination, a fire-box, means to deliver fuel into said fire-box, and means to scatter said fuel as delivered, comprising a continuous blast of fluid under pressure which blast is of undulating intensity. 40

NATHAN M. LOWER.
